DESIGN FOR AN EYEGLASS FRAME OR SIMILAR ARTICLE

Stefan Kaesz, Brooklyn, N. Y.

Application October 23, 1946, Serial No. 134,188

Term of patent 14 years

(Cl. D57—1)

To all whom it may concern:

Be it known that I, Stefan Kaesz, a citizen of the United States, residing at Brooklyn in the county of Kings and State of New York, have invented a new, original, and ornamental Design for an Eyeglass Frame or Similar Article, of which the following is a specification, reference being had to the accompanying drawing, forming part thereof.

In the drawing:

Fig. 1 is a perspective front view of the eyeglass frame or similar article showing my new design;

Fig. 2 is a plan view of the same, the temples being shown fragmentarily for convenience of illustration.

The features of my invention reside in the portions shown in the drawing in full lines.

I claim:

The ornamental design for an eyeglass frame or similar article, as shown and described.

STEFAN KAESZ.
